BOTTLE

Melvin E. St. Clair, Hartford, Conn., assignor to
Plax Corporation, West Hartford, Conn., a corporation of Delaware

Application October 7, 1952, Serial No. 21,743

Term of patent 14 years

(Cl. D58—6)

To all whom it may concern:

Be it known that I, Melvin E. St. Clair, a citizen of the United States, residing at Hartford, State of Connecticut, have invented a new, original, and ornamental Design for a Bottle, of which the following is a specification, reference being had to the accompanying drawing, forming a part hereof.

Fig. 1 is a plan view of a bottle embodying my new design.

Fig. 2 is a front elevational view of the bottle shown in Fig. 1; and

Fig. 3 is a side elevational view of the bottle as seen from the right of Fig. 2.

I claim:

The ornamental design for a bottle, as shown.

MELVIN E. ST. CLAIR.
